SHUTTLE REPLENISHING MECHANISM

Ivano Mulatti and Luigi Cremonini, Milan, Italy

Application December 11, 1948, Serial No. 64,866
In Italy December 15, 1947

13 Claims. (Cl. 139—243)

1 This invention relates to cop-changing mechanisms for looms, and has for an object to provide an improved mechanism which will introduce a fresh cop into the shuttle when the cop in the shuttle is exhausted, the feeding of the fabric being momentarily interrupted without stoppage of the loom, and to stop the loom at once without introducing a fresh cop should the weft break.

Mechanism according to the invention comprises a cop magazine and a guideway disposed adjacent one end of the slay of the loom; a plunger movable towards and from the slay and adapted to expel the lowermost cop from the guideway; a weft-detecting fork pivoted on one end of a radius rod mounted on a fixed pivot; a hook reciprocable by the loom mechanism and engageable by a loop on the weft detecting fork; a bell-crank lever pivoted to the radius rod and spring-urged against a stop on the radius rod, one arm of said bell-crank lever being formed with a slot; a cop feeler pivoted to a fixed support and adapted, when swung on its pivot, to cause a hook to engage the slot in the bell-crank lever; a cop-changing control lever mechanism actuated by movement of the bell-crank lever and adapted to prepare the plunger for actuation by the slay; a cloth take-up control lever mechanism actuated by movement of the radius rod and adapted to stop the cloth take-up mechanism; and a stop lever actuated by movement of a second arm of the bell-crank lever, and connected to the stop mechanism of the loom.

The guideway may be slotted at one end for passage of an end of the yarn of each cop.

The plunger may carry a rack meshing with a toothed sector member mounted on a fixed pivot, said sector member being spring-urged to turn in a direction to move the plunger away from the slay, and carrying a push rod pivoted to the sector member and engageable with a projection on the slay, said push rod being movable into engagement with the slay by an actuating lever which is part of the cop-changing control lever mechanism.

A practical embodiment of the invention is illustrated in the accompanying drawings in which Fig. 1 is a sectional view taken on line 1—1 of Fig. 5, showing the cop-changing mechanism proper; Fig. 2 illustrates the arrangement of the cops in the guideway; Fig. 3 illustrates a shuttle; Fig. 4 is an elevation view of the needle shown in Fig. 3; Fig. 5 is an elevation view of the device showing the cooperative relationship of the various parts, including the weft-detecting fork and the cop feeler; Fig. 6 is a sectional view taken on line 6—6 of Fig. 5 showing the weft-de-

10 tecting hook, its reciprocating means and its co-operation with the weft-detecting fork and loop; Fig. 7 is a view showing the arrangement of the cop feeler and associated hook; Fig. 8 illustrates two positions of the weft-detecting fork with respect to the weft-detecting hook; Fig. 9 illustrates parts of the cop-changing control and feed control mechanisms; and Fig. 10 illustrates the position of the radius rod and bell-crank lever immediately after the weft is broken.

15 In the drawings, 1 denotes the cheeks, and 2 denotes the walls of the cop magazine and guideway. 3, 3a and 3b are cops, 3a denoting the cop in the shuttle and the cop positioned for replacement, 3b the cop in the magazine above 3a, and 3 the remaining cops in the magazine. At 5 is shown a plunger to which is fixed a rack 6 meshing with a toothed sector member 7 furnished with an extension 8 and pivoted at 9 to a bracket 10. A push rod 12 is pivoted at 11 to the extension 8 of the sector member, and formed with a fork 13 engageable with a projection 15 on the slay. An actuating lever 14 is adapted to raise the push rod 12 to the dotted-line position 12A. At 16 is shown a tension spring connected to the sector 7. 17 denotes a tongue adapted to support the stack of cops in the guideway, and 18 represents a slot in one of the cheeks 1 for passage of one end 19 of the yarn on each cop.

20 A shuttle 20 is formed with a laterally open cavity 21. 23 denotes a needle fixed at 22 within the cavity 21 and formed with an offset point 24 and an eye 25, in one wall of which is formed a slot 26.

25 At 27 is shown a radius rod pivoted at 28 to a fixed bracket 29. A cradle 30 is fixed to the radius rod 27. A weft-detecting fork 31 is pivoted at 32 to one arm 33 of a bell-crank lever passing through an opening 34 between the sides of the cradle and pivoted at 35 to a fixed support, the outer end of the other arm 36 of the bell-crank lever bearing against the cam 37, which cam is rotatable by a shaft 38. A bell-crank lever 39 is pivoted at 40 to the radius rod 27 and urged by a spring 41 against a stop 42 on the radius rod 27. At 43 is shown a spindle carried in bearings 44 and supporting a cop feeler 45 and a hook 46 engageable with a slot 47 in one arm of the bell-crank lever 39. 48 denotes the weft, and 49 denotes the reed of the loom attached to the slay 50. A loop 51 is carried by the weft-detecting fork 31 and is engageable with the weft-detecting hook 52. 53 denotes a cop-changing control lever pivoted at 54 and 55, respectively, to fixed supports. 56 and 57 represent actuating rods connected to the levers

84 and 85, respectively. At 90 is shown the slotted arm of the bell-crank lever 65, and a second arm is shown at 91, said second arm being engageable with a stop lever 93, connected to the stop mechanism of the loom and adapted to stop the loom when in the position indicated at 93a. 92 denotes a tongue on the radius rod 52, movable to actuate the cloth take-up control lever 85.

During normal operation of the loom, the cam 63 rotates and causes the hook 57 to reciprocate. The reed 76, in moving to and fro, presses the weft 75 against the weft-detecting fork 56, causing it to swing about its pivot 55 and raise the loop 78 clear of the reciprocating hook 57, as the hook 57 moves in the direction away from the weft-detecting fork 56. Consequently, no movement is transmitted to the radius rod 52.

When the cop in the shuttle is exhausted, there is no weft to swing the weft-detecting fork 56. The loop 78 is engaged by the hook 57 and pulled rearwardly by the hook 57. The weft-detecting fork 56 being pivoted to the cradle 54, the cradle is moved along with the hook 57, the radius rod 52 thereby being caused to swing about the pivot 53. At this time the cop feeler 71 encounters no resistance and enters the cavity 21 in the shuttle, thus causing movement of the hook 72 to a position where the hook is out of engagement with the slot 73. Since the arm 91 of the bell-crank lever 65 is resiliently held by the spring 67 the slotted arm 90 of the bell-crank lever 65 moves with the radius rod 52 and contacts the lever 84 to swing said lever 84 about its pivot 86. The actuating rod 88 raises the actuating lever 14, which in turn swings the push rod 12 into the position 12a. When the slay moves towards the cop magazine, the projection 15 engages the forked end 13 of the push rod 12 and pushes the rod 12 rearwardly, thereby partially rotating the sector member 7 about its pivot 9 in opposition to the spring 16. The rotational movement of the sector 7 moves the rack 6 and the plunger 5 towards the slay, the plunger 5 pushing the filled cop 3a into the shuttle 20. At the same time as the arm 90 moves the lever 84, the tongue 92 on the radius rod 52 actuates the cloth take-up control lever 85 which stops the cloth take-up mechanism, thereby preventing take-up of the woven cloth.

A fresh cop having been introduced into the shuttle, in the first flight of the shuttle the weft remains outside of the needle 23, but during the next flight, which is in the opposite direction to the first, the weft passes under the needle 23, past the point 24, and slides over the top of the needle until it reaches the slot 26, through which it passes into the eye 25.

If the weft breaks while the shuttle contains an unexhausted cop, there is no weft for the reed 76 to press against the weft-detecting fork 56. Consequently, the loop 78 is engaged by the hook 57 and the radius rod is swung about the pivot 53, as described above. The cop feeler 71 contacts the cop in the shuttle and is unable to move into the slot 21. The hook 72 therefore swings into engagement with the slot 73. When the radius rod 52 swings about its pivot 53, the bell-crank lever 65, being held captive by the hook 73, is caused to swing away from the stop 68 in opposition to the spring 67. The arm 91 of the bell-crank lever 65 contacts the stop lever 93 and forces it out of a retaining notch. The stop lever, when clear of the notch, springs to the stop position 93a, and the loom stops.

We claim:

1. In a weaving loom having a shuttle for carrying a weft and a slay providing a path for said shuttle, a cop-changing mechanism comprising a magazine and a guideway to receive and position filled cops, a plunger disposed adjacent one end of the slay and movable relative thereto, said plunger being adapted when moved toward said slay to expel one of the filled cops from said magazine into the shuttle, a radius rod mounted on a fixed pivot, weft-detecting means pivoted on said radius rod and adapted to cause movement thereof when said means is reciprocated, a hook adapted to engage said weft-detecting means, said means being so arranged with respect to the weft that it is caused to move out of engagement with the hook to prevent reciprocatory movement thereof when there is a weft in the loom, means for reciprocating said hook, means for moving said plunger toward said slay, and means actuated by movement of said radius rod to prepare said plunger moving means for actuation, whereby a filled cop is expelled from said magazine and into said shuttle when the cop in the shuttle becomes exhausted.

2. A cop-changing mechanism as claimed in claim 1 in which the guideway is slotted at one end for passage of an end of the yarn of each cop.

3. A cop-changing mechanism as claimed in claim 1 in which the means for moving the plunger toward the slay includes a toothed sector member rotatable about a fixed pivot, a rack mounted to effect movement of said plunger and meshing with said sector member, and means for causing rotation of said sector member upon movement of said slay toward said plunger when the shuttle cop is exhausted.

4. A cop-changing mechanism as claimed in claim 3 in which the plunger moving means has means for yieldingly urging the plunger away from the slay.

5. A cop-changing mechanism as claimed in claim 1 in which the means for moving the plunger towards the slay includes a toothed sector member rotatable about a fixed pivot, a rack meshing with said sector member movable to effect movement of said plunger, a projecting member mounted for movement with the slay, and a push rod lever operably connected to the sector member and movable when the cop in the shuttle is exhausted to a position such that said projecting member will contact said push rod lever and cause movement thereof to move said sector member when the slay approaches the plunger during normal movement of said slay, whereby said rack is caused to move the plunger toward the slay for expulsion of a filled cop into the shuttle when the cop in the shuttle becomes exhausted.

6. A cop-changing mechanism as claimed in claim 5 in which the means for preparing the plunger moving means for actuation includes a bell crank lever pivoted to the radius rod for movement therewith, a control lever mechanism having one element thereof so positioned with respect to said bell-crank lever that movement of the bell-crank lever causes actuation of said control lever mechanism and having another portion thereof so positioned with respect to the push rod that actuation of the control lever mechanism causes movement of the push rod to a position such that the projecting member will contact said push rod during normal movement of said projecting arm.

7. In a weaving loom having a shuttle for

carrying a weft, a slay providing a path for said shuttle and a loom stop mechanism, a cop-changing mechanism comprising a magazine and a guideway to receive and position filled cops, a plunger disposed adjacent one end of the slay and movable relative thereto, said plunger being adapted when moved toward said slay to expel one of the filled cops from said magazine into the shuttle, a radius rod mounted on a fixed pivot, weft-detecting means pivoted on said radius rod and adapted to cause movement thereof when said means is reciprocated, means for causing reciprocatory movement of said weft-detecting means, said weft-detecting means being adapted to be moved out of engagement with said reciprocatory-movement-causing means when there is a weft in the loom, a bell-crank lever pivoted to said radius rod between the ends thereof for movement therewith, a stop mounted on the radius rod, means yieldingly urging one portion of said bell-crank lever against said stop, means for moving the plunger toward the slay, means actuated by movement of said portion of the bell-crank lever to prepare the plunger-moving means for actuation, means for detecting the presence of an unexhausted cop in said shuttle, and means for holding said portion of the bell-crank lever against movement when an unexhausted cop is in the shuttle, whereby movement of the radius rod causes movement of a second portion of the bell crank lever to actuate the loom stop mechanism.

8. A cop-changing mechanism as claimed in claim 7 in which the means for detecting the presence of an unexhausted cop in the shuttle includes a cop feeler so mounted with respect to the shuttle that it assumes one position when there is an exhausted cop in the shuttle and a second position when there is an unexhausted cop in the shuttle.

9. A cop-changing mechanism as claimed in claim 8 in which the means for holding said portion of the bell-crank lever against rotation includes a hook mounted for movement with said cop feeler and adapted to engage said portion of the bell-crank lever and prevent rotation thereof when there is an unexhausted cop in the shuttle.

10. A cop-changing mechanism as claimed in claim 7 in which the weft-detecting means includes a fork mounted for rotation by the weft during a portion of the movement thereof, and a loop normally in operative relationship with the reciprocatory movement-causing means, said loop being adapted to be moved out of operative relationship with said reciprocatory movement-causing means when said fork is rotated by the weft.

11. In a weaving loom having a shuttle for carrying a weft, a slay providing a path for said shuttle and a cloth take-up mechanism, a cop-changing mechanism comprising a magazine and a guideway to receive and position filled cops,

5 a plunger disposed adjacent one end of the slay and movable relative thereto, said plunger being adapted when moved toward said slay to expel one of the filled cops from said magazine into the shuttle, a radius rod mounted on a fixed pivot, weft-detecting means pivoted on said radius rod and adapted to cause movement thereof when said weft-detecting means is reciprocated, means for causing reciprocatory movement of said weft-detecting means, said weft-detecting means being adapted to be moved out of engagement with said reciprocatory-movement-causing means when there is a weft in the loom, means actuated by movement of said radius rod to stop the cloth-take-up mechanism, means for moving the plunger toward the slay, and means actuated by movement of said radius rod to prepare said plunger-moving means for actuation, whereby a filled cop is expelled from the magazine into the shuttle and operation of the cloth-take-up mechanism is stopped when the cop in the shuttle becomes exhausted.

25 12. A cop-changing mechanism as claimed in claim 11 in which the means for stopping the cloth-take-up mechanism includes a tongue mounted for movement with the radius rod, a cloth-take-up control lever so positioned that movement thereof is caused when the tongue is moved, and means so operably connecting said control lever to the cloth-take-up mechanism that movement of the control lever stops the cloth-take-up mechanism.

30 13. A cop-changing mechanism as claimed in claim 11 in which the weft-detecting means includes a fork mounted for rotation by the weft during a portion of the movement thereof, and a loop normally in operative relationship with the reciprocatory movement-causing means, said loop being adapted to be moved out of operative relationship with said reciprocatory movement-causing means when said fork is rotated by the weft.
